PLASTIC ATOMIZER

Gerard B. Robinson, Mount Gilead, Ohio

Application July 15, 1943, Serial No. 494,766

8 Claims. (Cl. 299—88.5)

This invention relates to nebulizers or atomizers for producing a dry vapor that is used for medication of the respiratory organs.

An object of the invention is to provide a nebulizer or atomizer that has an internal chamber constructed and arranged in a manner that the heavy drops of vapor will be deflected from the discharge opening of the nebulizer so that only dry vapor will escape from the nebulizer chamber.

Another object of the invention is to provide a nebulizer that is constructed of plastic materials, and is more particularly constructed in cooperating left and right hand halves that can be secured together to produce a complete nebulizer or atomizer.

Another object of the invention is to provide a nebulizer constructed from plastic material that is constructed and arranged in a manner that the atomizing head may be tested as a complete assembly before placing the same in the nebulizer.

Another object of the invention is to provide a nebulizer constructed from plastic material that may be produced by the injection molding process, and wherein the atomizing head as well as the body of the nebulizer are constructed in cooperating left and right hand halves to permit formation of the various small fluid passages required in the nebulizer when the cooperating halves are brought into their assembled relationship.

Another object of the invention is to provide a new and improved form of atomizing head.

Another object of the invention is to provide a method of manufacturing a nebulizer or atomizer constructed and arranged in accordance with any of the foregoing objects.

Further objects and advantages will become apparent from the drawing and the following description.

In the drawing:

Figure 1 is a vertical cross sectional view of the nebulizer or atomizer of this invention.

Figure 2 is a transverse cross sectional view taken along line 2—2 of Figure 1 showing the contour of the chamber of the nebulizer.

Figure 3 is a transverse cross sectional view taken along line 3—3 of Figure 1 showing the contour of the chamber at the level of the section line.

Figure 4 is a transverse cross sectional view of the chamber showing the contour thereof at the level of the section line.

Figure 5 is a transverse cross sectional view 55

taken along line 5—5 of Figure 1 showing the cross section of the atomizing head as well as the shape of the chamber at this level.

Figure 6 is a transverse cross sectional view taken along line 6—6 of Figure 1.

Figure 7 is a vertical cross sectional view of the lower portion of the nebulizer showing a modified form of an atomizing nozzle.

Figure 8 is a front elevational view of the atomizing nozzle illustrated in Figure 7.

Figure 9 is a cross sectional view showing a front modified form of atomizing nozzle.

Figure 10 is a horizontal cross sectional view taken along line 10—10 of Figure 8.

In this invention the nebulizer or atomizer consists of a body 10 that is constructed in two parts 11 and 12 that are similar in all respects in that they are left and right half portions of the body. The body parts 11 and 12 are provided with identical and cooperating recesses 13 and 14, respectively, that are adapted to be brought together on the parting line 15 whereby a chamber 16 is formed within the body 10. Additional recesses 17 and 18 are provided in the body parts 11 and 12, respectively, so that when associated together at the parting line 15 they will form a passage 19 for conducting air to within the chamber 16 through an atomizing head 20 that is positioned within the body 10.

The atomizing head 20 consists of two body parts 21 and 22, each of which has a U-shaped recess 23 and 24, respectively, which when brought into association at the parting line 25 of the atomizing head 20 forms a U-shaped channel or passage 26. One end of the channel 26 is connected to the passage 19 in the body 10 to receive inlet air while the opposite end of the channel 26 forms a discharge orifice 27 whereby the air is directed upwardly through the chamber 16 in the body 10. Additional recesses 28 and 29 are provided in the body parts 21 and 22 of the atomizing head 20 to form a L-shaped channel 30, one end of which is open at the bottom surface of the atomizing head 20 and the opposite end 31 is positioned over the center of the discharge opening 27 of the air passage 19 so that the air jet discharging from the opening 27 over the end 31 of the passage 30 will draw fluid through the passage 30 for discharging the same into the chamber 16.

The atomizing head 20 is positioned within recesses 32 and 33 provided in the body parts 11 and 12 near the lower portion thereof, as illustrated in Figure 1.

The upper end of the chamber 16 communicates with a discharge opening 34 that is positioned within a nose piece 35 through which the vapor will discharge from the chamber 16.

The air inlet passage 19 is provided with a fitting 36 that is positioned in a tapered hole 37 provided in the body 10, the fitting 36 providing means for connecting a rubber tube 38 to the body 10, the tube 38 having a bulb 39 on the free end thereof.

The body 10 of the atomizer is provided with a curved wall portion 40 that is disposed vertically above the discharge opening 27 of the inlet air passage so that the jet of air discharging upwardly, and carrying fluid from the passage 30, will impinge upon the surface of the curved wall 40. The wall portion 41 of the chamber 16 is provided with an arcuately shaped head portion 42 that also tends to collect the heavy droplets of atomized fluid. It will be noted that the outlet 34 is disposed on one side of the body 10, and particularly on the side of the body that is out of the direct path of the atomized fluid that is being directed upwardly by the air jet from the discharge opening 27 of the inlet air passage. Thus, only dry vapor will escape through the nose piece 35.

The atomizing head 20 consisting of the parts 21 and 22 will be assembled by cementing or otherwise securing the two cooperating left and right hand halves of the atomizing head together along their parting line 25 thereby forming the passages 26 and 30. This atomizing head may now be tested as a unit to determine if its operation is satisfactory before assembling the same into a nebulizer body. The atomizing head 20 may then be placed in one of the recesses 32 or 33 of the body parts 11 and 12 and secured therein by suitable means such as a liquid cement. The cooperating body part may then be assembled upon the body part containing the atomizing head 20 and the two parts be cemented together along the parting line 15, or secured together by any other suitable means.

Since the body parts 11 and 12 of the atomizer, and the parts 21 and 22 of the atomizing head 20 are constructed in cooperating left and right hand halves, it is apparent that the manufacture of the device will be relatively inexpensive as well as relatively easy. Since all of the recesses in the various parts are provided in one face of the respective parts, that they are particularly adapted to be produced by a molding process, and if the dies are accurate and well-made the various passages in the parts will properly align. The molding of the parts may be accomplished either by compression molding or by the injection molding process. Preferably, the parts 11, 12, 21 and 22 are made from a synthetic resinous material that is adapted to be compression or injection molded. The plastic parts may be held together by means of suitable cements for causing adherence between plastic materials. Also, the member 36 is adapted to be molded by the compression or injection molding process so that the entire nebulizer or atomizer can be produced at a relatively low cost by the compression or injection molding processes.

The chamber 16 is provided with a particular cross section which varies throughout the length of the chamber in the manner illustrated in Figures 2 to 6, inclusive. In Figures 4 to 6 there is shown the contour of the chamber 16 between the levels of the section lines positioned on Figure 1. The particular shape of this portion of the

chamber 16 is not of extreme importance because this portion of the chamber acts as a reservoir for the fluid that is to be atomized. However, the contour of the cross section of the chamber 16 reduces in its cross section from the cross section line 4-4 to the cross section line 3-3, shown in Figure 1, until the chamber assumes the shape, as illustrated in Figure 3, from the larger and more elongated contour, illustrated in Figure 4. Thus, the chamber is somewhat restricted at the level of the section line 3-3 so that the atomized fluid will be forced into engagement with the wall surface 40 of the chamber 16. It will be noted that the restriction in the cross sectional area of the chamber 16 at the level of the section line 3-3 has been occasioned by the outwardly bulging wall surface 40 which is positioned vertically above the discharge opening 27 of the inlet air passage 19.

Since the air jet leaving the discharge opening 27 will pick up or aspirate fluid from the passage 30 it will be forced to impinge against the wall portion 40 since it is moving in a vertically upward direction, the jet will thus be deflected in a leftward direction, as viewed in Figure 1, somewhat as illustrated by the dotted lines B. When the atomized fluid impinges against the wall portion 40, the heavy droplets of fluid will condense on this surface and drain by gravity along the surface back into the reservoir in the lower portion of the atomizer body. Also, the droplets will have a substantial period of time in which to collect upon the surface 40 because the atomized liquid will tend to wipe across the surface 40 and thus cause condensation of the heavy droplets.

The atomized liquid that reaches the chamber 16 between the section lines 3-3 and 2-2 on Figure 1, or that portion illustrated by the letter B, will consist only of the finer droplets of liquid together with what may be termed as dry vapor.

It will be noted that the cross sectional area of the chamber 16 increases toward the upper portion of the chamber as illustrated in Figure 2, so that the velocity of the atomized liquid will be reduced in the enlarged chamber so that the heavier of the fine drops of atomized fluid may collect along the wall portion 41 and in the dome 42 of the chamber 16, it being remembered that the atomized liquid was directed against these wall portions by the wall portion 40. This arrangement thereby provides a second surface upon which any of the droplets of atomized fluid can condense and drain back into the reservoir along the wall portion 41. Thus, only dry vapor will be discharged through the nose piece 35 to be inhaled into the respiratory organs whereby there will be substantially no condensation in the nose of a person inhaling the dry vapors so that the vapors can pass deeply into the respiratory organs. It is, of course, understood that in order to operate the atomizer that the bulb 39 will be squeezed intermittently to force air through the inlet passage 19. It is also understood that in place of the bulb 39 that the device may be connected to a suitable source of compressed air so as to throw a more or less continuous vapor through the nose piece 35.

In Figures 7, 8 and 10 there is illustrated a modified form of atomizing head for use in the nebulizer or atomizer of this invention. The atomizing head 45 in this instance may be constructed in two parts along a parting line 46 in the same manner as heretofore described, the parting line being arranged so as to permit the

production of the desired passages in the head 45.

The atomizing head 45 consists of a body portion 49 that is slightly tapered in an upward direction, as viewed in Figure 8. Grooves 50 and 51 are provided in opposite edges of the body 49 and are interconnected by means of groove 52 extending across the top of the body 49. The air inlet passage 26a discharges upwardly through the groove 52, as illustrated in Figure 7.

The functioning of the atomizer head 45 is such that the liquid is drawn by capillary attraction upwardly along the tapering grooves 50 and 51 toward the top groove 52, whereby the top groove 52 is always filled with liquid. Movement of air through the passage 26a blows the liquid from the groove 52 to atomize the same and at the same time causes an increase in the movement of the fluid through the grooves 50 and 51 whereby the air stream discharging from the passage 26a will be supplied with liquid for atomizing or vaporizing the same.

The quantity of liquid that is drawn through the grooves 50 and 51 may be controlled by the size of the grooves. It is, of course, understood that the control of the liquid is such that the grooves cannot be of such large size that the liquid loses the effect of the capillary attraction in its movement upwardly through the grooves.

In Figure 9 there is illustrated a further modified form of atomizing head that functions in the same manner as that illustrated in Figures 7 and 8 wherein the head 55 is provided with small angularly disposed channels 56 that discharge into a transverse groove 57, the air supply for the device being through the inlet passage 58.

While the apparatus disclosed and described herein constitutes a preferred form of the invention, yet it is to be understood that the device is capable of mechanical alteration without departing from the spirit of the invention, and that all such modifications as fall within the scope of the appended claims are intended to be included herein.

Having thus fully described my invention what I claim as new and desire to secure by Letters Patent is:

1. An atomizer or nebulizer consisting of, a body having an elongated chamber therein that is substantially elliptical in transverse cross section, an atomizing head disposed in the lower portion of said chamber for directing fluid longitudinally through said chamber, said chamber having the wall portion thereof at one end of the elliptical shape thereof extending toward the center of the chamber and having a deflecting surface thereon positioned directly in the path of movement of the atomized liquid passing longitudinally through said chamber whereby to cause condensation of heavy droplets of atomized liquid thereon, and a discharge opening for atomized vapor to discharge from said chamber positioned above said wall portion and on the same side of said elliptical chamber as said wall portion.

2. An atomizer or nebulizer including in combination; an atomizing head consisting of a pair of body parts having co-operating and engaging face portions, a channel recess in each of said engaging face portions forming one half of an air inlet channel, and a second channel recess in each of said face portions having one end thereof disposed immediately adjacent one end of said first channel recess and forming one half of a fluid passage, said co-operating parts having said face portions thereof secured together to form complete channel portions in the atomizing head; and

an atomizer body consisting of co-operating body parts each of which includes a recess portion for forming one-half of an atomizing chamber and one half of an outlet passage associated therewith, a second recess in each of said atomizer body parts adjacent the end thereof opposite to the discharge end and forming means for receiving said atomizing head, whereby co-operation of said body parts forms an atomizing chamber therein and retains said atomizing head in position within said chamber.

3. An atomizer or nebulizer which consists of; a plastic atomizing head, an air inlet passage in said head, a fluid passage in said head having one end thereof disposed in alignment with the discharge end of said air inlet passage and arranged in planar alignment with said air inlet passage whereby said head can be made in two co-operating parts divided along a plane extending longitudinally through the centers of said passages, a plastic body, a chamber in said body for receiving atomized liquid, a discharge passage from said chamber having an axis thereof in planar alignment with a plane extending longitudinally through the center of said chamber, a recess in said body to receive said atomizing head and having a plane through the longitudinal center thereof in planar alignment with said plane through the center of said chamber whereby said body can be made in two co-operating parts and secured together on a plane of parting which coincides with the plane of parting through said atomizing head.

4. An atomizer or nebulizer consisting of, a body having an elongated atomizing chamber therein, an atomizing head positioned in the lower portion of said chamber for directing fluid longitudinally through said chamber, wall means in said chamber extending transversely thereof toward the center of said chamber and having a deflecting surface thereon positioned directly in the path of movement of the atomized liquid passing longitudinally through said chamber to deflect the atomized liquid against an opposite wall of said chamber whereby to provide a plurality of surfaces engaged during the longitudinal movement of the atomized liquid through said chamber for condensing heavy droplets of atomized liquid, and a discharge opening for atomized vapor to discharge from said chamber positioned above said extending wall portion and on the same side of said chamber as said extending wall portion to thereby receive only dry vapor.

5. An atomizer or nebulizer consisting of, a body having an elongated chamber therein that is substantially elliptical in transverse cross section, an atomizing head positioned in the lower portion of said chamber for directing fluid longitudinally through said chamber, said chamber having the wall portion thereof at one end of the elliptical shape thereof extending toward the center of the chamber and having a deflecting surface thereon positioned directly in the path of movement of the atomized liquid passing longitudinally through said chamber to deflect the atomized liquid against the opposite end wall portion of the elliptically shaped chamber whereby to cause condensation of heavy droplets of atomized liquid on the surface of the wall portions, and a discharge opening for atomized vapor to discharge from said chamber positioned above said extending wall portion and on the same side of said elliptically shaped chamber as said extending wall portion to thereby receive only dry vapor from the upper portion of said chamber.

6. An atomizer or nebulizer consisting of, a body having an elongated chamber therein, an atomizing head positioned in the lower portion of said chamber for directing fluid longitudinally through said chamber, said chamber having wall means extending transversely toward the center of said chamber to reduce the cross-sectional area of the chamber and having a deflecting surface thereon engaged by the atomized liquid passing longitudinally through said chamber for deflecting the path of movement of the atomized liquid during its longitudinal forward movement through the chamber to cause the same to engage the wall of said chamber opposite to the position of said extending wall portion whereby to cause a double condensation of heavy droplets of atomized liquid, and a discharge opening for atomized vapor to discharge from said chamber positioned above said extending wall means and on the same side of said chamber as said extending wall means whereby to receive only dry atomized vapor.

7. An atomizer or nebulizer consisting of, a body having an elongated chamber therein, a discharge opening from said chamber positioned at one end of said chamber and to one side thereof relative to a longitudinal central axis through the chamber whereby to provide a substantial top wall portion that has an unbroken surface joined to an immediate side wall portion of the chamber, said chamber having a side wall portion extending transversely toward the center of said chamber and positioned directly beneath said discharge opening and having a deflecting surface thereon for causing deflection of atomized liquid passing

longitudinally through said chamber, and an atomizing head positioned in the opposite end of said chamber for directing a stream of atomized liquid against said deflecting surface for deflection against said top and co-extensive side wall of said chamber to thereby condense heavy droplets of atomized liquid.

8. An atomizer or nebulizer consisting of, a body having an elongated chamber therein, a discharge opening for atomized vapor to discharge from said chamber positioned in one end thereof and on one side of said chamber relative to a longitudinal axis through the same, said chamber having a wall portion extending transversely toward the center of the chamber and positioned directly beneath said discharge opening and having a deflecting surface thereon for deflecting atomized liquid toward the opposite wall of said chamber, and an atomizing head positioned adjacent the opposite end of said chamber for directing atomized liquid against said deflecting surface and including a body member, a passage in said body inclined angularly inwardly toward the center of said body of such small size that liquid moves upwardly through the passage by capillary attraction, a horizontal passage in the upper edge of said body communicating with said first mentioned passage and an air inlet passage in said body and having the discharge end thereof positioned to discharge air through said last-mentioned passage whereby liquid in this last-mentioned passage is discharged therefrom by the passage of air therethrough.

GERARD B. ROBINSON.
